DRESSING APPARATUS

Albert Vuilleumier, Bristol, Conn., assignor to
General Motors Corporation, Detroit, Mich., a
corporation of Delaware

Application October 5, 1934, Serial No. 747,085

12 Claims. (Cl. 125—11)

This invention relates to dressing apparatus for grinding wheels and the like and comprises all of the features of novelty herein disclosed. An object of the invention is to provide a dressing apparatus which will perform its work at less cost than heretofore, especially in respect to the cost of the dressing tool itself. Another object is to provide an improved automatic dressing apparatus for abrading tools. Another object is to provide improved means for feeding and controlling the movements of a dressing tool or the like.

To these ends and also to improve generally upon devices of this character, the invention consists in the various matters hereinafter described and claimed. In its broader aspects, the invention is not necessarily limited to the specific construction selected for illustrative purposes in the accompanying drawings in which

Fig. 1 is a front elevation of the apparatus, with parts of the supporting structure in section.

Fig. 2 is a detail front view of a portion of the apparatus to large scale.

Fig. 3 is a plan view with some parts in section.

Fig. 4 is a sectional view about on the line 4—4 of Fig. 3.

Fig. 5 is a horizontal sectional view about on the line 5—5 of Fig. 4.

Figs. 6 and 7 are detail views of friction braking discs.

Fig. 8 is a vertical sectional view of a portion of the apparatus, the section being taken at right angles to that of Fig. 4.

Fig. 9 is an elevation of the dressing wheel holder, with a portion in section.

Fig. 10 is a diagram of electrical and fluid pressure connections.

First outlining the general operation of an embodiment selected merely for illustration, a grinding wheel G, with a cylindrical face or faces to be dressed, is rotated around its axis while a rotary dressing wheel D is reciprocated along an element of the cylinder, the rotation of the dressing tool being produced by frictional contact with the grinding wheel but being retarded by a brake. As the dressing tool reciprocates, a ratchet wheel is intermittently turned to effect relative rotation of screw threaded members thereby slowly feeding the dressing wheel towards the grinding wheel.

The grinding wheel G is enclosed in a guard 10 having a portion slabbed off flat to receive a guide plate 12 which is fastened by screws 14, there being interengaging shoulders at 16 to position the guide plate laterally. A slide 18

reciprocates along the guide plate on a guide rail 20 of inverted V-shape and on flat ways 22, a rear gib 24 being fastened to the guide plate by screws 26 and a front gib 28 being secured by screws 30. To protect the front ways 22 from dirt, a shield 32 is fastened by screws to the gib 28 and has a downturned lip 34 entering a groove in the slide. The slide has a tubular bearing extension or projection 36 which projects downwardly through an elongated slot 38 in the guide plate 12 and through a registering slot 40 in the wheel guard 10. To exclude grit from working up to the ways through the slots, an elongated cover strip 42 is fitted around the extension 36 above the slot 38 and is arranged to slide along in a shouldered recess of the guide plate, the cover plate being made long enough to cover the slot in any position of the slide.

A cylinder 44 is formed integrally with or secured to the rear of the slide 18 to shift with the latter and contains a fixed piston 46 secured to a hollow piston rod formed in two sections 48 abutting against a partition 50 fixed in the piston. Each section has longitudinal slits 52 registering with radial grooves 54 in the sides of the piston, thus to form ports connecting the interior of the cylinder with the interior of the piston rod sections. The sections project through cylinder heads 56 having packing glands 58 and their remote ends are secured in bracket arms 60 by set screws 62. The bracket arms project forwardly and upwardly from brackets 64 secured to lugs 66 on the ends of the guide plate 12.

Pipes 68 and 70 are connected to the piston rod sections and to a reversing valve 72 (Fig. 10) having a piston rod 74 with a pair of spaced pistons 76. Pressure fluid enters the valve through a supply pipe 78 and exhaust fluid leaves the valve alternately through the exhaust pipes 80 and 82. Solenoids 84 and 86 have their plungers connected to the piston rod 74 to shift the latter under control of switches 88 and 90 which are contained (Fig. 1) in switch boxes 92 fastened to the ends of the brackets 64. To shift the switches alternately and automatically, the reciprocating cylinder 44 carries adjustable headed screws 94 arranged to engage pins 96 slidably supported by the brackets 64 and suitably connected to the switches. One of the pins 96 slides in a threaded bushing 98 as indicated at the right of Fig. 1, the bushing forming a stop for the headed screw 94. Both Fig. 1 and Fig. 10 show the cylinder at its extremity of movement to the right with the switch 88 closed, thus energizing the solenoid 84 and shifting the valve to a position 55

tion in which pressure fluid will pass from the valve to the pipe 68 and then to the left end of the main cylinder to shift the cylinder to the left. This action will in turn close the switch 90, 5 energize solenoid 86, and reverse the valve. Pressure fluid will then go from the valve through the pipe 70 to return the cylinder, etc., so that the reciprocating cylinder controls its own reversal.

10 The dressing wheel D is rotatably mounted (as will appear) in a hollow carrier or quill 100 which is slidable up and down in the slide 18 and its bearing extension 36, thus to feed the dressing wheel downwardly towards the grinding wheel. 15 The quill has a keyway 102 engaged by a key 104 (Fig. 8) which is fastened in a groove of the slide 18 by screws 106. This construction prevents rotation of the quill but allows downward feeding. The quill is threaded externally throughout 20 its upper portion and engages at 108 with internal threads at the upper portion of a sleeve 110 which is rotatably supported and centered on the slide 18 by an annular shoulder or lip 112. A bridge or yoke 114 (Fig. 1) has vertical legs fastened by 25 bolts 116 to lugs 118 on the slide 18, thus to leave a space where a ratchet 120 on the sleeve 110 will be exposed. A collar 122 is secured by a set screw 124 (Fig. 4) to the rotary sleeve 110 in a position spaced above the bridge 114. A dog 30 carrying hub 126 is journaled for turning movement on the sleeve below the collar and is supported on the bridge 114. An arm 128 projects rearwardly from the hub in a position to engage an abutment screw 130 (Fig. 3) which is adjust- 35 ably secured by a nut in a bracket arm 132, the contact of the arm 128 with the screw giving the hub a partial turning movement whenever the slide 18 reaches the right hand limit of movement. The amount of turning movement is controlled by adjusting the position of the abutment screw 130. Another arm 134 projects forwardly and downwardly from the hub and has a boss in which a ratchet dog 136 is slidably mounted. A leaf spring 138 fastened by a screw to 40 the hub 126 extends downwardly back of a shoulder on the dog to urge the latter against the ratchet teeth. The dog can be manually retracted from the ratchet by a hand wheel 142 and can then be locked out by turning its cross pin 144 crosswise of a vertical notch which it normally engages.

45 A coil spring 146 (Figs. 3 and 5) is secured at one end to a pin 148 on the hub 126 while its other end is anchored to a pin 150 on the bridge 114, thus to always move the hub clockwise when it has been moved counterclockwise by engagement 50 of the arm 128 and the abutment screw 130. The ratchet dog 136 is of course oscillated with the hub but the rotary sleeve 110 is held from retrograde movement by a detent dog 152 which is slidably mounted in the bridge and urged against the ratchet 120 by a leaf spring 154. The dog has a hand wheel 156 and a cross pin 158 so that it can be manually retracted and locked as in 55 the case of the dog 136. The two dogs are thus locked out when a down feed of the quill 100 has been completed and it is desired to elevate it to starting position. Fig. 4 shows the quill near its lower limit of movement. As a limit to the action of the coil spring 146 in turning back the hub 126, a stop pin 160 projects from the hub in a position to engage the screw which fastens the leafspring 154 to the bridge.

60 At the lower end of the quill 100 in a recess thereof is a double row ball bearing 162 having

its outer race ring clamped by an end cap 164. Near the upper end of the quill is a single row ball bearing 166 whose outer race ring has a sliding fit in the quill. The two inner race rings are secured to a hollow rotary spindle 168, being 5 spaced apart by a spacing and braking sleeve 170 which is keyed near its upper end to the spindle. The inner race rings and the spacing sleeve are 10 clamped together endwise as a unit by nuts 172 threaded on the upper end of the hollow spindle, the lower inner race ring abutting against a shoulder on the spindle.

15 There are internal keyways 174 near the upper end of the quill into which project lugs 176 on friction discs 178 surrounding the spindle and clearing the latter. The discs 178 alternate with friction discs 180 which clear the quill but have lugs 182 projecting into keyways 184 in the sleeve 170 above a supporting flange 186. On the uppermost disc 178 is supported a weight 188 in the 20 form of a ring. This weight is so selected as to give the desired amount of braking friction between the discs so that the rotation of the spindle 168 will be retarded, thus causing the grinding wheel and the dressing wheel to have different 25 speeds when the former drives the latter by frictional contact. As shown in Fig. 1, the quill 100 is at a small angle to the plane of the end face of the grinding wheel G, or, otherwise stated, the axis of the dressing wheel is a little out of a line 30 normal to the grinding wheel, so that the grinding wheel meets the dressing wheel on one side only of the axis of the dressing wheel. The dressing wheel has an end face that is in the surface of a shallow cone and this conical surface has a 35 line of contact with an element of the cylindrical grinding wheel. The frictional engagement of these parts causes the dressing wheel to be driven at a speed determined by the weight 188, other factors remaining constant. 40

45 A chuck plate 190 at the lower end of the hollow spindle 168 has an internal conical face to wedge with a similar face on a circular holder 192 which has radial slits 194 to make the holder expandable and contractible, thus to grip a ring 196 of lead or the like which is molded to the dressing wheel D. The radial slits extend up into a hollow projection or stud 198 of the holder and this stud is keyed to the chuck spindle by a pin 200. The upper end of the stud is threaded as 50 at 202 to engage threads on the lower end of a draw rod 204 having a socketed head 206 engaging the upper end face of the spindle. By turning the draw rod, the holder is drawn upwardly 55 into the chuck plate and the conical faces contract the holder to grip the dressing wheel.

60 In operation, whenever it is desired to dress off the grinding wheel G, the dressing wheel D is brought down to the grinding wheel by turning the sleeve 110, the ratchet dogs being temporarily retracted. The pressure fluid for the reversing valve 72 is then set in operation and the electric current turned on. The main slide 18 carrying the quill 100 then reciprocates automatically as described above, carrying the dressing wheel D 65 along the grinding wheel G. Contact of the rotating grinding wheel with the rotary dressing wheel frictionally drives the latter but the speed of the latter is retarded by the brake so that surface speeds are different and cutting will occur. 70 Wheel D is preferably of softer abrasive than wheel G. Whenever the slide reaches the end of its stroke in one direction, the arm 128 engages the abutment screw 130, and the hub 126 carrying the ratchet feed dog 136 is oscillated through 75

a small angle. This action slowly turns the threaded sleeve 110 with respect to the threaded quill and such intermittent down feed is continued until the surface of the grinding wheel is true. The dressing wheel and the quill are then raised from the grinding wheel by turning the threaded sleeve 110 in the opposite direction while the ratchet dogs are again temporarily retracted.

I claim:

1. In apparatus of the character described, a dressing wheel having a spindle, a carrier rotatably supporting the spindle, means for frictionally driving the dressing wheel, co-operating friction discs between the spindle and the carrier, and a weight for holding said discs in engagement.

2. In apparatus of the character described, a dressing wheel having a spindle, means for frictionally driving the dressing wheel, a sleeve keyed to the spindle, brake discs keyed to the sleeve, a quill rotatably supporting the spindle, brake discs keyed to the quill, and means for urging the brake discs together.

3. In apparatus of the character described, a wheel guard having a slot, a guide plate on the wheel guard and having a slot, a slide movable on the guide plate and having a projection extending through said slots, a dressing tool shiftable with the slide and having a mounting in the slide and its projection, and an elongated cover plate secured to the slide around the projection and closing the slots.

4. In apparatus of the character described, a wheel guard having a slot, a slide shiftable lengthwise of the slot and having a tubular projection, a sleeve extending through the slide and its projection, a dressing tool carried by the sleeve, and an elongated cover plate secured around said slide projection and closing the slot.

5. In apparatus of the character described, an abrading wheel, a slide shiftable with respect to the wheel, a carrier sleeve shiftable endwise in the slide, a bridge carried by the slide, a rotary member supported by the slide and having threaded engagement with the carrier sleeve, a ratchet wheel secured to the rotary member, a dog carrying member supported on the bridge and having a dog engaging the ratchet wheel, and means for oscillating the dog carrying member to turn the rotary member for effecting endwise movement of the carrier sleeve.

6. In apparatus of the character described, an abrading wheel, a slide shiftable with respect to the wheel, a carrier sleeve shiftable endwise in the slide, a spindle inside the sleeve and journaled for rotation therein, a dressing wheel on the spindle, a rotary member supported by the slide and having threaded engagement with the carrier sleeve, a ratchet wheel secured to the rotary member, a hub journaled on the rotary member and having an actuating arm, the ratchet wheel and the hub surrounding the carrier sleeve in concentric relation thereto and the hub member surrounding the rotary member, a dog carried by the hub and engaging the ratchet wheel, and an abutment arranged to engage the arm of the hub upon the shifting of the slide.

7. In apparatus of the character described, an abrading wheel, a slide shiftable with respect to the wheel, a carrier sleeve shiftable endwise in the slide and towards the abrading wheel, a dressing wheel rotatably supported by the car-

rier sleeve and frictionally engaging the abrading wheel, brake members housed in the carrier sleeve and concentric therewith for retarding rotation of the dressing wheel, a sleeve rotatably supported by the slide and having threaded engagement with the carrier sleeve, and means for causing the shifting movement of the slide to turn the rotatably supported sleeve to feed the dressing wheel in the direction of its axis of rotation.

8. In apparatus of the character described, an abrading wheel, a slide shiftable with respect to the wheel, a pair of sleeves, one of the sleeves being shiftable endwise through the slide and held from rotation, the other sleeve being rotatably mounted on the slide and held from endwise movement, the sleeves having portions in threaded engagement with one another, means for causing the shifting movement of the slide to turn the rotatable sleeve, a dressing tool having a spindle rotatably carried by the non-rotatable sleeve and shiftable therewith, the dressing tool having a surface for frictional driving engagement with the abrading wheel, and brake mechanism mounted within the non-rotatable sleeve for retarding the rotation of the dressing tool.

9. In apparatus of the character described, an abrading wheel, a slide shiftable with respect to the wheel, a carrier sleeve extending through the slide and shiftable endwise therein, a spindle rotatable in the carrier sleeve, a dressing tool on the spindle for frictional driving engagement with the abrading wheel, brake mechanism mounted within the carrier sleeve and reacting with the spindle to diminish the speed of the dressing tool, a threaded sleeve rotatably supported on the slide and having its internal surface in threaded engagement with the carrier sleeve, and means for shifting the slide to turn the threaded sleeve.

10. In apparatus of the character described, an abrading wheel, a slide shiftable with respect to the wheel, a carrier sleeve extending through the slide and shiftable endwise therein, a spindle extending through the carrier sleeve and journaled for rotation therein, a dressing wheel on the spindle and frictionally engaging the abrading wheel, means for causing the shifting movement of the slide to effect endwise movement of the carrier sleeve, and braking means interposed between the carrier sleeve and the spindle.

11. In apparatus of the character described, an abrading wheel, a slide shiftable with respect to the wheel, a carrier sleeve extending through the slide and shiftable endwise therein, a spindle journaled for rotation in the carrier sleeve, a dressing wheel on the spindle and frictionally engaging the abrading wheel, means for causing the shifting movement of the slide to effect endwise movement of the carrier sleeve, brake discs carried by the spindle and the carrier sleeve, and means for urging said brake discs into contact.

12. In apparatus of the character described, a carrier sleeve, a spindle journaled for rotation in the sleeve, a dressing wheel on the spindle and frictionally driven, brake members carried by the spindle and by the sleeve, and means for urging the brake members into contact to retard rotation of the dressing wheel.
